SAIL SLIDE

Charles Hugh Duffy, Miami, Fla.

Application May 17, 1934, Serial No. 726,123

7 Claims. (Cl. 114—112)

(Granted under the act of March 3, 1883, as amended April 30, 1928; 370 O. G. 757)

The invention described herein may be manufactured and used by or for the Government for governmental purposes, without the payment to me of any royalty thereon.

5 This invention relates to a sail slide for improving the air-flow to the sail.

Heretofore there has been a great loss in the aerodynamic efficiency of sails because of the fact that the usual hoops or slides made no provision for closing the opening or space normally existing between the luff or other edge of a sail and its mast or spar, and thereby permitted a break in the continuity of the air-flow to the sail and allowed to be set up at and adjacent 10 such openings or spaces adverse aerodynamic influences which detracted from the efficiency of the sail.

20 This improved sail slide has for its inventive purpose to insure under all conditions and positions of a sail, that the luff or other edge of a sail be snugly maintained in close association with its mast or other spar to the end that the usual opening or space between the sail and the mast or spar is closed and the continuity of the 25 air-flow to the sail maintained and its aerodynamic efficiency increased.

This invention consists of the novel construction of the sail slide and in its provision for attachment to the sail.

30 Referring to the accompanying drawing:

Fig. 1 is a plan view of the metal blank out of which the slide is formed;

Fig. 2 is a similar view of another preferred form;

35 Fig. 3 is an end elevation of the slide formed from the blank shown in Fig. 1;

Fig. 4 is a similar view of the slide formed from the blank shown in Fig. 2;

Fig. 5 is a side elevation of the slide formed 40 from the blank shown in Fig. 1;

Fig. 6 is a similar view of the slide formed from the blank shown in Fig. 2;

Fig. 7 is a top plan view of the slide formed from the blank shown in Fig. 1;

45 Fig. 8 is a top plan view of the slide formed from the blank shown in Fig. 2;

Fig. 9 is an end elevation of the slide having its bails modified and bent down directly upon the bolt rope;

50 Fig. 10 is a side elevation of the same;

Fig. 11 is an end elevation of the slide with sail connecting link connected to one of the slide bails;

55 Fig. 12 is an end elevation of the slide with

link connecting the sail, the sail slide and mast assembly being shown in cross section;

Fig. 13 is a similar view showing the sail squared off to one side in full lines and squared off to the opposite side in dotted lines, and 5

Fig. 14 is a fragmentary side elevation of the assembly shown in Fig. 12.

Like numerals of reference indicate the same parts throughout the several figures, in which:

A indicates the metal blank of which the slide 10 is formed.

In forming the slide 1 from the blank shown in Fig. 1, in which each vertical side edge is provided with two transverse cuts 2, the two end portions 3 of each vertical side are formed downwardly and inwardly for engagement with a track as shown in Fig. 3, while the central bail portions 4 which are each perforated as at 5 and are formed up vertically from the back of the slide as also shown in Figs. 3 and 7. 15

In forming the slide 1 from the blank shown in Fig. 2, the two vertical edge portions 6 are uninterrupted and are formed downwardly and inwardly into positions shown in Fig. 4, while the two bail portions 4 which are each perforated as at 5 are struck up vertically out of the body of the blank, into position shown in Figs. 4 and 8. 20

For small light sails and particularly along the foot thereof, the vertical bails 4 may be made longer and closer together, so that the bolt-rope 11 sets snugly between the two bails 4 and closely against the back of the slide 1. The bails are then bent directly down and upon each side of the bolt-rope as shown in Figs. 9 and 10 so that no other sail attaching means is required. 25

Referring to Fig. 11, either of the embodiments shown in the Figures 1 to 8 may have permanently attached to one of the perforated vertical bails 4 a link 7 of stout strong wire. The central portion 8 of the link is formed arcuately and its free end 9 is bent to be conveniently passed through the eye of a grommet 10 in the sail 12 and through the other of the perforated bails 4, after which the end 9 of the link is bent upwardly and over the bail 4 into an eye as shown in Fig. 12. This operation brings the bolt-rope 11 of the sail 12 snugly against the back of the slide 1, as shown in Fig. 12 thereby closing the space or opening normally existing between the bolt-rope and the slide and mast or other spar and increasing the aerodynamic efficiency of the luff portion or other edge portion to which a series of these slides are attached. 35

From Figs. 12 and 13 in which the slide 1 is 55

shown in operative position on its track 13 and mast or other spar 14, it will be seen that the luff of the sail is free to swing through a full arc of 180 degrees from the position shown in full lines in Fig. 13 to position shown in dotted lines in this figure, and is free to assume all intermediate positions without pinching or binding and at the same time insuring a snug contact of the bolt-rope with the back of the slide.

10 In Fig. 14, the assembly is shown in elevation, and while only a single slide is illustrated, it is of course understood that a series of these slides are applied in closely spaced formation along the luff of the sail from head to tack, and may also 15 be employed along the foot of the sail from tack to clew or along the gaff of gaff headed sails, but wherever employed they effectually close up the aerodynamically disadvantageous space or 20 opening normally existing between the sail and its spar.

As will appear from the drawing, the slide may be employed without the link 8 whenever it is desired to lash or sew the slide to the sail. In such cases, the bolt-rope lies against the back 25 of the slide as shown in dotted lines in Figs. 3 to 8, and the lashing or sewing threads are passed through the perforated bails 4 and through the grommet or bolt-rope of the sail.

It is characteristic of the several embodiments 30 of this sail slide shown in the drawing and described in this specification, that there projects downwardly from the body portion of the slide, the necessary track-engaging portions and that there projects upwardly from the body portion 35 of the slide the two upstanding bails 4. This definite construction of the slide is accomplished by stamping and forming the body, the downwardly projecting track-engaging portions and the upwardly projecting upstanding bails, integral 40 and out of a unitary piece of metal.

It is further characteristic of this sail slide construction that the two upstanding bails lie parallel with the bolt-rope of the sail so as to straddle the bolt-rope and insure that the bolt 45 rope lies snugly against the face of the body of the slide and between the two upstanding bails thereof. It is further characteristic of the sail slide that the upstanding bails are devoid of swinging or pivotal movement with respect to the 50 slide body and its track engaging means.

Having thus described the preferred embodiments of the invention, it may be obvious to those skilled in the art that the slide may be otherwise constructed than as shown in the three examples 55 in the drawing. Therefore I do not wish to limit myself to the exact constructions shown and described but consider myself clearly entitled to all such changes and modifications as fall within the limit and scope of the following claims.

60 What I claim as new and desire to secure by Letters Patent of the United States is:

1. A slide for attachment to a spar having a track of the character described for slidably connecting a sail and its bolt-rope to the track including vertical side edge portions formed downwardly and inwardly for engagement with the track, a part of each vertical side edge portion being formed upwardly to provide a vertical bail at each side edge of the slide, a stiff metallic link 65 having a central arcuate portion and ends for connection with each vertical of said bails, each bail including means to connectingly receive the ends of said link, said link being adapted to be passed through the sail adjacent its bolt-rope to 70 maintain the bolt-rope of the sail between the two vertical bails and snugly against the back of the slide, the whole characterized by the fact that the downwardly and upwardly formed vertical 75

maintain the bolt-rope of the sail between the two vertical bails and snugly against the back of the slide.

2. A slide for attachment to a spar having a track of the character described for slidably connecting a sail and its bolt-rope to the track including vertical side edge portions formed downwardly and inwardly for engagement with the track, a part of each vertical side edge portion being formed upwardly to provide a bail at each vertical side edge of the slide, a link for connection with each of said bails, each vertical bail including means to connectingly receive the ends of said link, said link being adapted to be passed through the sail adjacent its bolt-rope to maintain the bolt-rope of the sail between the two vertical bails and snugly against the back of the slide.

3. A slide for attachment to a spar having a track of the character described for slidably connecting a sail and its bolt-rope to the track having side edges and including means for connection with the track, a part of each vertical side edge portion of the slide being formed upwardly to provide a vertical bail at each side edge of the slide, a link for connection with each of said vertical bails, each bail including means to connectingly receive the ends of said link, said link being adapted to be passed through the sail adjacent its bolt-rope to maintain the bolt-rope of the sail between the two vertical bails and snugly against the back of the slide, the whole characterized by the fact that the means for connection with the track are integral with the upwardly formed vertical bails and devoid of any swinging movement with respect thereto.

4. A slide for attachment to a spar having a track of the character described for slidably connecting a sail and its bolt-rope to the track including vertical side edge portions formed downwardly and inwardly for engagement with the track, a part of the slide adjacent each vertical side edge thereof being formed upwardly to provide a vertical bail at each side edge of the slide, a stiff metallic link having a central arcuate portion and ends for connection with each of said vertical bails, each bail including means to connectingly receive the ends of said link, said link being adapted to pass through the sail adjacent its bolt-rope to maintain the bolt-rope of the sail between the two vertical bails and snugly against the back of the slide, the whole characterized by the fact that the downwardly and upwardly formed vertical side portions for engagement with the track are integral with the upwardly formed vertical bails and devoid of any swinging movement with respect thereto.

5. A slide for attachment to a spar having a track of the character described for slidably connecting a sail and its bolt-rope to the track including vertical side edge portions formed downwardly and inwardly for engagement with the track, a part of the slide adjacent each vertical side edge thereof being formed upwardly to provide a bail vertical at each side edge of the slide, a link for connection with each of said vertical bails, each bail including means to connectingly receive the ends of said link, said link being adapted to be passed through the sail adjacent its bolt-rope to maintain the bolt-rope of the sail between the two vertical bails and snugly against the back of the slide, the whole characterized by the fact that the downwardly and upwardly formed vertical

tical side portions for engagement with the track are integral with the upwardly formed vertical bails and devoid of any swinging movement with respect thereto.

5 6. A slide for attachment to a spar having a track of the character described for slidably connecting a sail and its bolt-rope to the track including means for connection with the track, a part of the slide adjacent each vertical side edge thereof being formed upwardly to provide a vertical bail at each side edge of the slide, a link for connection with each of said vertical bails, each bail including means to connectingly receive the ends of said link, said link being adapted to be passed through the sail adjacent its bolt-rope to maintain the bolt-rope of the sail between the two vertical bails and snugly against the back of the slide, the whole characterized by the fact that the means for connection with the track are integral with the up-

wardly formed vertical bails and devoid of any swinging movement with respect thereto.

7. A slide for attachment to a spar having a track of the character described for slidably connecting a sail and its bolt-rope to the track including vertical side edge portions formed for connection with the track, a stiff metallic link having a central arcuate portion and ends, the slide including means adjacent each of the vertical side edges of the slide to connectingly receive the ends of the link, the link being adapted to be passed through a sail adjacent its bolt-rope to maintain the bolt-rope snugly against the back of the slide, the whole characterized by the fact that the vertical side edge portions for connection with the track are integral with the means for connectingly receiving the ends of the stiff metallic link and devoid of any swinging movement with respect to said means.
